UNITED STATES PATENT OFFICE.

SAMUEL SYLVESTER JOHNSON AND MARK E. JOHNSON, OF HARRISBURG, PENNSYLVANIA.

SIGNAL DEVICE OR INDICATOR.

1,381,561.

Specification of Letters Patent. Patented June 14, 1921.

Application filed August 21, 1919. Serial No. 318,959.

To all whom it may concern:

Be it known that we, SAMUEL S. JOHNSON, and MARK E. JOHNSON, citizens of the United States, residing at Harrisburg, in the county of Dauphin and State of Pennsylvania, have invented certain new and useful Improvements in Signal Devices or Indicators; and we do hereby declare the following to be a full, clear, and exact description of the invention, such as will enable others skilled in the art to which it appertains to make and use the same.

The present invention relates to a signal device or indicator designed especially for use on automobiles and other motor vehicles, and aims to provide a novel and improved device of that character for signaling to the traffic and pedestrians the intentions of the operator to turn or stop, so as to avoid collisions and accidents.

It is the object of the invention to provide a novel and improved means for mounting the signal member for turning movement, whereby the signal will be both attractive and conspicuous.

Another object is the provision of novel means for operating the signal member to give the signals.

A still further object is the provision of a signal member and operating means therefor, mounted on a post or standard in a novel and effective manner, which post can also be used as a support for a mirror or reflector for observing traffic in rear.

It is also the object to provide such a device which will be comparatively simple and inexpensive in construction, as well as being easy to operate and not liable to get out of order.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:—

Figure 1 is a side elevation of the improved signal device.

Fig. 2 is a plan view thereof.

Fig. 3 is a vertical median section of the device.

Fig. 4 is an enlarged horizontal section

taken on the line 4—4 of Fig. 3, showing the electrical circuits diagrammatically.

A tubular post or standard 1 is used as a support for the signal device, having its lower end screw threaded or otherwise secured within a base 2 that is secured on a suitable support of the machine, such as the fender 3 of one of the front wheels, thereby disposing the device in a convenient and conspicuous position. This post 1 can be used to support a mirror or reflector 4 which is pivotally connected to the upper end thereof, in order that the operator may observe traffic in rear, to avoid collisions and accidents.

Signal member 5 comprises an arrow-shaped frame having the glass or transparent sides 6, and a vertical hub or sleeve 7 between the ends of said member or frame mounted for rotation on the post 1, whereby the signal member can turn about a vertical axis, in a horizontal plane. An apron ring 8 is secured on said post and is fitted loosely over the upper protruding end of the sleeve 7, to prevent moisture from passing downwardly into said sleeve. Mounted within the signal member, which is hollow, is a lamp socket 9 in which an electric lamp 10 is mounted for illuminating the signal member during the night time, and the electrical conductors or wires 11 extend from the socket 9 through holes in the sleeve 7 and post 1 so as to extend downwardly through and out of the post to the source of electrical current. This lamp can be lighted during darkness, so that the signal can be observed at night as well as during the day time.

In order to support the signal member for free rotary movement and to inclose the actuating means for the signal member, a cup shaped casing 12 is mounted on the post 1 below the signal member, being provided at its bottom with a boss 13 embracing the post and secured thereto by means of a set screw 14 or the like. The signal member 5 is mounted on a turntable 15 disposed over the casing 12, and provided with depending aprons or flanges 16 on the outer and inner sides of the rim or edge of the casing 12, to prevent moisture and dirt from entering said casing. A disk 17 is secured on the post 1 in any suitable manner within the casing, and said disk and turntable 15 are provided with confronting ball races 18 in which anti-friction balls 19 travel, whereby

they support the turntable and signal member for free turning movement, the ring 8 holding the signal member down on its mounting.

- 5 The casing 12 houses actuating means for the signal member, which actuating means, as shown, comprises a pair of arcuate solenoids 20 disposed within the casing, and an arcuate core 21 carried by a bracket or hanger 22 attached to the inner apron or flange 16, so that said core is connected to the turntable and signal member. The ends of the core enter the solenoids, and when one solenoid is energized, it will draw the 10 core into it, so as to turn the turntable and signal member in one direction, whereas the signal member is turned in the opposite direction from normal position when the other solenoid is energized. The signal member 15 is retained in normal longitudinal position pointing straight forward by means of a suitable spring 26 which permits the signal member to turn toward either side, to point toward the right or toward the left, and when the respective solenoid is energized, the spring will return the signal member to its normal position.

Each solenoid is disposed in an electrical circuit 23, and said circuits have a common 20 battery 24 or other source of electrical energy, and a controlling switch 25 operable manually at the steering wheel, instrument board or other suitable point, for closing said circuit, whereby to energize one solenoid or the other to turn the signal member accordingly. The conductors or wires 25 of the electrical circuits can extend down through the post 1.

It is also possible to use other operating 30 means for controlling the signal member,

which may be housed within the casing 12 and extended through the post 1 to a point to be operated by the hand or foot.

The signal member will operate easily and quickly, and affords convenient and efficient 45 means for signaling the intentions of the operator to steer toward one side or the other, or to stop, so that operators of other vehicles as well as pedestrians will be warned. The signal member and its mounting will also be ornate and attractive in appearance, providing a desirable adjunct to the machine, in connection with the mirror 4.

Having thus described the invention, what 55 is claimed as new is:—

A signal device comprising a post, a signal member having a sleeve mounted for rotation on said post between the ends thereof, a cup-shaped casing having its bottom 60 secured on said post under the signal member, a turntable over said casing supporting the signal member and having an apron surrounding the casing, means for supporting said turntable for free rotation above 65 said casing, a ring on the post engaging over the upper end of said sleeve to hold the signal member and turntable down and to prevent moisture and dirt from entering said sleeve, and actuating means within said casing connected to said turntable for turning it.

In testimony whereof we have signed our names to this specification in the presence of two subscribing witnesses.

SAMUEL S. JOHNSON.
MARK E. JOHNSON.
